WALLET WITH CHANGE PURSE

Leo G. Mueller, West Roxbury, Mass., assignor, by
mesne assignments, to Swank, Inc., a corpora-
tion of Delaware

Application August 22, 1946, Serial No. 692,281

4 Claims. (Cl. 150—38)

1

This invention relates to a wallet and particularly to the formation of a change purse therein. The formation of a pocket for coins or change in a wallet of this character has provided some difficulties in view of the fact that the pocket for carrying such articles must be securely closed and it has often been necessary to provide additional pieces of material for the formation of such pocket which requires attachment of these pieces of material for this purpose. Difficulty has been experienced in the formation of wallets where leather is utilized which has an outer surface carrying a high finish and a rough inner surface which cannot well be exposed to view and will not readily wear. It therefore becomes necessary in many cases to provide additional plies of material in order that the proper face of the material may be exposed.

One of the objects of this invention is to provide a wallet which will be formed from a single piece of material.

Another object of this invention is to provide a wallet in which the change purse may be formed of a single piece of material even though this material has a finished surface on one side and a rough surface on the other.

Another object of this invention is to so fold a piece of material having two different surfaces that the finished surface will be outermost in all of the exposed parts of the wallet.

With these and other objects in view, the invention consists of certain novel features of construction, as will be more fully described and particularly pointed out in the appended claims.

In the accompanying drawings:

Fig. 1 is a perspective view of the wallet in folded position;

Fig. 2 is a top plan view of a blanked out section of material which has the essential shape for the formation of a wallet;

Figs. 3 and 4 are additional pieces of material which may be utilized if desired in the wallet where the same is of a structure that has different faces on the material used;

Fig. 5 is a perspective view of one of the metal fastenings utilized; and

Fig. 6 is a perspective view of another of the metal fastenings utilized for holding the wallet in assembled position;

Fig. 7 is a plan view of the parts shown in Figs. 2, 3, and 4 assembled;

Fig. 8 is a view similar to Fig. 7 but showing the parts in folded relation;

Fig. 9 is a sectional view on line 9—9 of Fig. 8;

Fig. 10 is a section on line 10—10 of Fig. 7;

2

Fig. 11 is a view similar to Fig. 8 but showing the parts in further folded relation;

Fig. 12 is a plan view showing the ends which extend in Fig. 11 as folded into finished position;

5 Fig. 13 is a section on line 14—14 of Fig. 12;

Fig. 14 is a section on line 14—14 of Fig. 12;

Fig. 15 is a perspective view of the wallet in finished assembled relation;

10 Fig. 16 is a perspective view of one end of the wallet showing the change purse and the cover of the change purse in opened relation;

Fig. 17 is a longitudinal central sectional view through the wallet with the parts shown in closed position;

15 In proceeding with this wallet I cut from sheet stock a blank such as shown in Fig. 2 and assemble therewith such additional parts as may be necessary if the stock is formed from material having a finished surface on one side and an

20 unfinished surface on the other. The change pocket of the purse is formed by folding the stock in such a manner that an opening may be provided in one section while a section beneath it in forming another wall of the pocket will present

25 the same surface material. This may be accomplished by providing three sections of material folded one upon the other. A cover may be formed by a flap extending from an additional section which may cover the opening to the

30 change pocket.

With reference to the drawings, a blank is cut out as shown in Fig. 2 in which there is provided a section 20 having a lip 21 extending along one edge. This section is of a length substantially twice the finished folded length of the wallet as shown in Fig. 1 and is provided with flaps 22 and

35 23 extending from its opposite ends. Sections 24 and 25 are joined to the sides of this section 20 but are separated from each other by an opening 26. A tab 27 is located at the end of this opening and a lip 28 extends inwardly from the end of section 24. Section 24 is also provided with an opening 29 which serves as a mouth or entrance

40 30 for the change pocket. On the other side of the section 24 and along the fold line there is provided another section 30 which is formed of two-ply material by reason of a portion 30' which extends from an end thereof along a fold line 31 and

45 is doubled over the ply 30. Another section 32 is provided along the side of the section 25 which is also separated by the space 26 from the section 30. Section 33 shown in Fig. 3 may be added to

50 provide a dividing wall for separating bills while

55 a section 34 is provided to provide an inner lining

for the entrance portion of card pockets which are utilized.

In assembling the sections shown in Figs. 2, 3, and 4, the section 33 is positioned beneath the sections 30 and 32 as shown by the dotted line (Fig. 7) while a section 34 is positioned above the sections 30, 32 as shown in Fig. 7. The upwardly arched portion 36 is shown through the opening 26 in this figure. Cement or stitching at one edge thereof as shown in Fig. 10 may be utilized for securing the section 33 to the sections 30, 32 while it is merely necessary to place the section 34 in position or it may be stitched as desired as shown at 34' in Fig. 10. The section 36' is doubled in over the section 30 and 34 along the fold line 31 and then the parts are doubled in again along the fold line 38 as shown in Fig. 7 and into the position shown in Fig. 8 so as to bring the section 33 uppermost. The lip 28 is folded over the inner edge of the section 30' and there cemented in position to form the bottom of the change pocket. Section 34 extends across beneath the sections 30 and 32. The tab 27 is also folded over and cemented as shown. After the sections are thus folded, they are again folded along the fold line 39 into the position shown in Fig. 11 where the sections 24 and 25 are brought outermost and in this position the flap 22 is folded over and held in position by a strap 40 having finger 41 extending from either end thereof to pass through slits 42 in the flap 22 and 43 in the section 25 to hold this end of the wallet assembled. The flap 23 at the other end of the wallet is folded over the section 24 and is secured by a metal fastener 45 (see Fig. 5) extending through slits 46 in the flap and 47 in the section 24. This leaves the cutout 29 as an entrance opening to the pocket the bottom of which is closed by the folding of the lip 28 over the section 30'. A snap fastener 48 may be provided on this flap 23 to engage a stud 49 which is positioned in the section 24 so as to hold these parts assembled. The section 34 extends between the section 30 and the section 30' and provides a finished surface for entrance into a pocket thus formed.

From the foregoing, it will be apparent that I have provided a wallet having bill retaining portions 50 and 51 on either side of the wall or section 33. There is also a pocket provided as at 52 for cards or the like between the section 32 and 25 at one end while at the other end there is provided a card receiving section 53 and a change pocket 54 closed by a lip 28 at one end

and the flap 23 at the other as shown in the sectional view in Fig. 17.

I claim:

1. In a wallet, a change pocket formed from a single piece of sheet stock, comprising a face section having an opening therein adjacent to but spaced from its outer end, a two-ply section of similar size and shape and joined thereto along a fold line at one side edge thereof and in surface contact therewith, said two-ply section being formed by doubling the sheet stock along a fold line at right angles to the fold line joining it to the face section, a lip on the face section extending over the edge of the ply nearest the face section and cemented thereto to form a bottom of a pocket, the entrance to which is said opening in the face section and a third section of similar size and shape to the face section and joined to the face section along a fold line at the other side edge thereof and in surface contact with said two-ply section, said third section being provided with a flap at its outer end joined thereto by a fold line at right angles to the fold line joining it to the face section and extending over the face section to cover the marginal edges of the opening provided therein, and releasable means on the flap and face section to hold said flap in position to close said opening.

2. In a wallet as set forth in claim 1 wherein the sheet stock has a smooth surface and a rough surface and said folding of the two-ply section is such that the smooth surface is exposed through the opening in the face section.

3. In a wallet as set forth in claim 1 wherein said flap and two-ply section are held secured together by means interposed between said opening and the fold line for the flap.

4. In a wallet as set forth in claim 1 wherein the end edges of said folded two-ply section distant from said flap are unattached to each other and provide an additional pocket.

LEO G. MUELLER.
